Primary Examiner — Mary Ann Calabrese(74) Attorney, Agent, or Firm — Faegre Baker Daniels LLP(57) CLAIM

The ornamental design for a conference center, as shown and described.

DESCRIPTION

FIG. 1 is a front perspective of a conference center according to a first embodiment of my new design;

FIG. 2 is a front view thereof;

FIG. 3 is a right side view thereof; and

FIG. 4 is a left side view thereof.

FIG. 5 is a front perspective of a conference center according to a second embodiment of my new design;

FIG. 6 is a front view thereof;

FIG. 7 is a right side view thereof; and,

FIG. 8 is a left side view thereof.

The conference center is shown with a symbolic break in its length and width. The appearance of any portion of the article between the break lines forms no part of the claimed design.
